US009856656B2

(12) **United States Patent**
Pervan

(10) **Patent No.:** **US 9,856,656 B2**
(45) **Date of Patent:** ***Jan. 2, 2018**

(54) **MECHANICAL LOCKING OF FLOOR PANELS WITH A GLUED TONGUE**

(71) Applicant: **Ceraloc Innovation AB**, Viken (SE)

(72) Inventor: **Darko Pervan**, Viken (SE)

(73) Assignee: **CERALOC INNOVATION AB**, Viken (SE)

(*) Notice: Subject to any disclaimer, the term of this patent is extended or adjusted under 35 U.S.C. 154(b) by 0 days.

This patent is subject to a terminal disclaimer.

(57) **ABSTRACT**

A tongue with edge sections that are used to glue the tongue into a groove of panel. A tongue for connection of a building panel, said tongue is of an elongated shape and made of molded plastic, the tongue including at least two protrusions at a first long edge of the tongue, wherein the protrusions are bendable in a plane parallel to the upper surface of the tongue and extending essentially in the parallel plane and, wherein the tongue has a second long edge, which is essentially straight over substantially the whole length of the tongue and the tongue includes a gluing part configured to be glued into a groove at an edge of the building panel.

MECHANICAL LOCKING OF FLOOR
PANELS WITH A GLUED TONGUECROSS REFERENCE TO RELATED
APPLICATIONS

The present application is a continuation of U.S. application Ser. No. 14/042,887, filed on Oct. 1, 2013, which is a divisional of U.S. application Ser. No. 13/540,107, filed on Jul. 2, 2012, which claims the benefit of U.S. Provisional Application No. 61/504,576, filed on Jul. 5, 2011, the benefit of Swedish Application No. 1150635-9, filed on Jul. 5, 2011, Swedish Application No. 1150775-3, filed on Aug. 26, 2011, and Swedish Application No. 1150777-9, filed on Aug. 29, 2011. The entire contents of each of U.S. application Ser. No. 14/042,887, U.S. application Ser. No. 13/540,107, U.S. Provisional Application No. 61/504,576, Swedish Application No. 1150635-9, Swedish Application No. 1150775-3, and Swedish Application No. 1150777-9 are hereby incorporated herein by reference in their entirety.

AREA OF INVENTION

The invention generally relates to the field of floor panels with mechanical locking systems with a flexible and displaceable tongue. The invention also relates to a partly bendable tongue for a building panel with such a mechanical locking system.

BACKGROUND OF THE INVENTION

In particular, yet not restrictive manner, the invention concerns a tongue for a floor panel and a set of floor panels mechanically joined to preferably a floating floor. However, the invention is applicable to building panels in general as well. More particularly invention relates to the type of mechanically locking system that comprises a flexible or partly flexible tongue and/or displaceable tongue, in order to facilitate the installation of building panels.

A floor panel of this type is presented in WO 2006/043893, which discloses a floor panel with a locking system comprising a locking element cooperating with a locking groove, for horizontal locking, and a flexible tongue cooperating with a tongue groove, for locking in a vertical direction. The flexible tongue, which may be made of plastic, bends in the horizontal plane and is displaced in a groove during connection of two floor panels. The flexible tongue allows the floor panels to be installed by vertical folding or solely by vertical movement.

The flexible tongues are generally connected into a groove with friction connections. One disadvantage with such connection is that the tongue may fall out from the groove when floor panels swell or shrink or when the groove is not made with sufficient tolerances.

It is known that the tongue may be glued into the groove. The problem is that it is difficult to glue plastic to wood and that part of the glue also glues the tongue in such a way that it cannot be displaced during the connection of the floor panels. The present invention provides a simple way to glue a flexible and displaceable tongue into a groove.

SUMMARY OF THE INVENTION

The aim of present invention is to provide a tongue that is easy to glue in a groove. Useful areas for the invention are floor panels, preferably to be installed floating, of any shape

2

and material e.g. laminate, wood, HDF, veneer or stone. However, the invention is applicable to building panels in general.

The tongue may be used in any mechanical locking system that facilitates the assembling of building panels. The tongue may be used in the mechanical locking system for vertical locking of two adjacent floor panels. The locking system may further comprise additional elements for horizontal locking of the adjacent floor panels.

A first aspect of the invention is a tongue for connection of a building panel, said tongue is of an elongated shape and made of moulded plastic. The tongue comprises protrusions, preferably bow shaped, at a first long edge of the tongue. The protrusions are bendable in a plane parallel to the upper surface of the tongue and extending essentially in the parallel plane. The tongue has a second long edge, which is essentially straight over substantially the whole length of the tongue. The tongue comprises a gluing part configured to be glued into a groove at an edge of the building panel.

The gluing part may be an edge section, which is spaced in the length direction of the tongue from the protrusions.

The edge section may comprise a glue pocket.

The edge section may comprise a flexible link that connects the edge section to the main tongue body.

The tongue may be provided with said edge sections at each edge of the tongue.

The advantage is that the edge sections are spaced from the main tongue body that is displaced during locking. The risk that glue will be applied in the part of the groove where the tongue has to be displaceable is eliminated.

The edge section may be provided with a breaking part, configured to be broken when the tongue is inserted into the groove.

The edge section may be provided with an outer protruding stop part, which overlaps an inner stop part, which protrudes from the edge of the tongue, wherein said inner and outer stop part cooperates to limit the displacement of the tongue in the groove.

The edge section may be provided with a protruding friction connection, configured to hold the tongue in the correct position until the glue is cured.

The gluing part may be a gluing strip extending in the longitudinal direction of the tongue, preferably along substantially the whole length of the tongue, and wherein the gluing strip is attached to the outer end of some of the protrusions.

The advantage with such a gluing strip is that the tongue is attached steady to the groove of the building panel and with an improved position tolerance. It is also easier to provide the glue along the bottom of the groove, which is made possible by this embodiment.

The outer end of the protrusions, at a first edge of the tongue, may be free and not attached to the gluing strip.

The outer end of the protrusions, at a second edge of the tongue, may be attached to the gluing strip.

The outer end of the protrusions may be provided with a thinner section for facilitating the bending of the protrusion.

The outer end of the gluing strip may be provided with a bow shaped part for facilitating the insertion of the tongue into the groove.

There may be an angle between the protrusions and the longitudinal direction of the tongue.

A second aspect of the invention is a building panel provided with a tongue, according to the first aspect, in a sidewardly open groove at edge of the panel.

BRIEF DESCRIPTION OF THE DRAWINGS

The disclosure will in the following be described in connection to exemplary embodiments and in greater detail with reference to the appended exemplary drawings, wherein:

FIG. 1 illustrates a known locking system comprising a displaceable tongue;

FIG. 2 shows a first embodiment of the tongue according to the invention;

FIGS. 3a and 3b shows an edge section of the first embodiment of the tongue

FIG. 4 shows a second embodiment of the tongue;

FIG. 5 shows first edge section of the second embodiment;

FIG. 6 shows second edge section of the second embodiment;

FIG. 7 shows a third embodiment of the tongue;

FIG. 8 shows first edge section of the third embodiment; and

FIG. 9 shows second edge section of the third embodiment.

DESCRIPTION OF EMBODIMENTS OF THE INVENTION

FIG. 1 shows a vertical locking of two panels where a flexible and displaceable tongue 1 is displaced in a fixing groove 2.

FIG. 2 shows a first embodiment of a flexible tongue 1, made of moulded plastic material, which comprises two edge sections 3, which are intended to be used to glue the tongue into a groove 2.

The tongue is of an elongated shape and comprising in this preferred embodiment at least two protrusions 6 at a first long edge L1.

The protrusions are bendable in a plane parallel to the upper surface of the tongue and extending essentially in the parallel plane.

The tongue has a second long edge L2, which is essentially straight over substantially the whole length of the tongue.

The edge section 3 comprises a glue pocket 4 where glue is applied, preferably by an inserting equipment, which also positions the tongue into a groove of a panel. Friction connections 7 may be used to hold the tongue in the groove until the glue cures.

FIG. 3a shows the edge section from above. FIG. 3b shows a cross section of the edge section. A glue pocket 4 is preferably formed as a local cavity.

The edge section is connected to the main tongue body with a flexible link 5 that allow the tongue to move in the groove 2 and in relation to the edge section 3 that is glued into a groove 2. A wide variety of glues may be used, preferably hot melt based glues.

FIG. 4 shows a second embodiment of a flexible tongue 1, made of moulded plastic material, which is provided with a gluing strip 8 configured to be used to glue the tongue into a groove 2. Parts 11, 12 formed by moulding inlets from a moulding tool are shown at the first 9 and the second edge 10 of the tongue 1. These parts are used to facilitate the insertion of the tongue into a groove 2 of a building panel, preferably a floor panel.

The tongue is of an elongated shape and comprising in the second embodiment at least two protrusions 6 at a first long edge L1.

The protrusions are bendable in a plane parallel to the upper surface of the tongue and extending essentially in the parallel plane.

The tongue has a second long edge L2, which is essentially straight over substantially the whole length of the tongue.

FIG. 5 shows the first edge 9 of second embodiment of the tongue. The outer ends 17 of the protrusions 6 at the first edge are free from the gluing strip 8 to facilitate a movement 10 of the second long edge L2 along the groove 2 of the building panel. The outer part of the gluing strip is bow shaped 16 to facilitate insertion of the tongue into the groove 2 of the building panel.

FIG. 6 shows the second edge 10 of second embodiment 15 of the tongue 1. The outer ends 18 of the protrusions 6 at the second edge are attached to the gluing strip 8. The outer part 16 of the gluing strip is bow shaped to facilitate insertion of the tongue into the groove 2 of the building panel.

The outer ends of the protrusions are provided with a thinner section 15 to improve the bending of the tongue.

The gluing strip is provided with a protrusion 13, which makes it easier to remove the tongue from the moulding tool. The tongue body is provided with an aperture 14 adapted to the size of the gluing strip protrusion 13, which make it 25 possible to push the second long edge L2 of the tongue 1 further into the groove 2 of the building panel.

FIG. 7 shows a third embodiment of a flexible tongue 1, made of moulded plastic material, which is provided with an edge sections 3 configured to be used to glue the tongue into 30 a groove 2. The tongue has a second long edge L2, which is essentially straight over substantially the whole length of the tongue. The tongue is of an elongated shape and comprising in the second embodiment at least two protrusions 6 at a first long edge L1.

Parts 11, 12 formed by moulding inlets from a moulding tool are shown at the first 9 and the second edge 10 of the tongue 1. These parts are used to facilitate the insertion of the tongue into a groove 2 of a building panel, preferably a floor panel.

40 The protrusions are bendable in a plane parallel to the upper surface of the tongue and extending essentially in the parallel plane.

FIG. 8 shows the first edge 9 of the third embodiment of the tongue.

45 FIG. 9 shows the second edge 10 of the third embodiment of the tongue 1.

The third embodiment of the tongue is provided with said edge sections 3 on each edge of the tongue. Said edge section is provided with a protruding friction connection, configured to hold the tongue in the correct position until the glue is cured. A flexible link 5 connects the edge section 3 to the main tongue body.

The edge sections are each provided with an outer protruding stop part 22, which overlap an inner stop part 21, 55 which protrudes from each edge 9, 10 of the tongue, wherein said inner and outer stop part cooperates to limit the displacement of the tongue 1 in the groove 2.

The edge sections are further provided with a breaking part 20, configured to be broken when the tongue 1 is 60 inserted into the groove 2.

Glue may be used that glues to a wood based material and cures such that a part of the glue will form a small protrusion in the glue pocket and will connect the tongue mechanically even if the glue as such cannot glue the plastic material that is used to form the tongue.

The principles shown above may be used to connect all types of tongues that are intended to be displaceable in a

groove. Even tongues that are not flexible and displaceable may be connected according to the described principles.

The invention claimed is:

1. A tongue for connection of a building panel, said tongue is of an elongated shape and made of moulded plastic, the tongue comprising:

an elongate main body of the tongue,
an edge section connected to at least one end of the
elongate main body,

a gluing part configured to be glued into a groove at an
edge of the building panel,

a first long edge including at least two protrusions, and the
tongue is configured so that the protrusions face toward
an inside the groove when the tongue is inserted into
the groove, and

a second long edge, opposite the first long edge, which
second long edge is straight over substantially a whole
length of the elongate main body of the tongue, and the
tongue is configured so that the second long edge
protrudes out of the groove when the tongue is inserted
into the groove,

wherein the gluing part is in the edge section of the
tongue, wherein the gluing part comprises a recess in
the edge section forming a glue pocket having an
opening which faces a wall of the groove when the
tongue is inserted into the groove, and the glue pocket
does not penetrate all the way through the edge section.

2. The tongue as claimed in claim 1, wherein the tongue
is provided with a flexible link that connects the edge section
to the elongate main body of the tongue, the flexible link
including a section that is more flexible than the elongate
main body of the tongue.

3. The tongue as claimed in claim 2,
wherein the protrusions are bendable in a plane parallel to
an upper surface of the tongue and extending essen-
tially in the plane, and

wherein the edge section is spaced in a length direction
along the first long edge of the tongue from the
protrusions.

4. The tongue as claimed in claim 3, wherein at least one
of the protrusions is provided with a protruding friction
connection, configured to hold the tongue in position until a
glue in the glue pocket is cured.

5. The tongue as claimed in claim 3, wherein the protrusions
are bow shaped.

6. The tongue as claimed in claim 3, wherein there is an
angle between the protrusions and a longitudinal direction of
the tongue.

7. The tongue as claimed in claim 2, wherein the tongue
is a monolithic construction made as one unitary piece.

8. The tongue as claimed in claim 2, wherein:
the elongate main body defines a main plane wherein the

first long edge extends along a first side of the elongate
main body facing in a first direction and the second
long edge extends along a second side of the elongate
main body facing in a second direction,

the at least two protrusions project in the main plane in the
first direction from the first side of the elongate main
body of the tongue,

the gluing part includes a surface that extends parallel to
the main plane, the recess being formed in the parallel
surface, and

when in a relaxed state, the second long edge extends
further in the second direction than the edge section and
the gluing part.

9. The tongue as claimed in claim 1, further comprising a
second edge section at an opposite end of the elongate main
body.

10. The tongue as claimed in claim 1, wherein the at least
two protrusions protrude in the same direction at the first
long edge of the tongue.

11. The tongue as claimed in claim 10, wherein the at least
two protrusions are bendable in a plane parallel to an upper
surface of the tongue and extend substantially in the plane.

12. The tongue as claimed in claim 1, wherein the tongue
is a monolithic construction made as one unitary piece.

13. The tongue as claimed in claim 1, wherein:
the elongate main body defines a main plane wherein the
first long edge extends along a first side of the elongate
main body facing in a first direction and the second
long edge extends along a second side of the elongate
main body facing in a second direction,

the at least two protrusions project in the main plane in the
first direction from the first side of the elongate main
body of the tongue,

the gluing part includes a surface that extends parallel to
the main plane, the recess being formed in the parallel
surface, and

when in a relaxed state, the second long edge extends
further in the second direction than the edge section and
the gluing part.

14. A building panel provided with a tongue, according to
claim 1, wherein said tongue is displaceable in a groove at
an edge of the building panel.

15. A tongue for connection of a building panel, said
tongue is of an elongated shape and made of moulded
plastic, the tongue comprising:

an elongate main body of the tongue,
an edge section connected to at least one end of the
elongate main body,

a gluing part configured to be glued into a groove at an
edge of the building panel,

a first long edge including at least two protrusions, and the
tongue is configured so that the protrusions face toward
an inside the groove when the tongue is inserted into
the groove, and

a second long edge, opposite the first long edge, which
second long edge is straight over substantially a whole
length of the elongate main body of the tongue, and the
tongue is configured so that the second long edge
protrudes out of the groove when the tongue is inserted
into the groove,

wherein the elongate main body defines a main plane
wherein the first long edge extends along a first side of
the elongate main body facing in a first direction and the
second long edge extends along a second side of the
elongate main body facing in a second direction,

wherein the gluing part is in the edge section of the
tongue, wherein the gluing part comprises a glue
pocket having an opening which faces a wall of the
groove when the tongue is inserted into the groove,

wherein the first long edge extends along a first side of the
elongate main body facing in a first direction and the
second long edge extends along a second side of the
elongate main body facing in a second direction,

the at least two protrusions project in the main plane in the
first direction from the first side of the elongate main
body of the tongue,

the gluing part includes a surface that extends parallel to
the main plane, the glue pocket being formed in the
parallel surface, and

when in a relaxed state, the second long edge extends further in the second direction than the edge section and the gluing part.

16. A method for fixing a tongue to a building panel, said tongue comprising:

an elongate main body,

a first long edge including at least two protrusions, the first long edge extending along a first side of the elongate main body, and

a second long edge, opposite the first long edge, which second long edge is straight over substantially a whole length of the elongate main body of the tongue and extends along a second side of the elongate main body,

an edge section connected to at least one end of the elongate main body, wherein the edge section includes a recess in the edge section forming a glue pocket, which glue pocket does not penetrate all the way through the edge section,

the method comprising:

5

putting glue into the glue pocket, inserting the tongue into a groove formed at an edge of the building panel so that the protrusions are inserted all of the way into the groove, the second long edge protrudes from the groove, and the edge section is within the groove, and

securing the edge section to the building panel with the glue.

17. The method as claimed in claim **16**, wherein a second edge section is connected to a second end of the elongate main body opposite the at least one end,

the second edge section includes a second recess in the second edge section forming a second glue pocket, which second glue pocket does not penetrate all the way through the edge section, and

when inserting the tongue into the groove, the second edge section is within the groove and is secured to the groove with glue.
